UNITED STATES PATENT OFFICE

2,603,118

LIGHT CONTROLLED MUSICAL
INSTRUMENT

Marcel Stanislas Ducout, Paris, France

Application August 10, 1949, Serial No. 109,433
In France September 21, 1948

13 Claims. (Cl. 84—1.18)

1

It is one of the objects of this invention to provide a musical instrument particularly for sound reproduction controlled at a distance by the movement of one or more dancers.

Ordinary musical instruments of the string or piano type require physical contact with the instrument, either through the hand of the musician or through an implement held by the musician. The instrument is actuated only when the hand engages the string or the piano directly or indirectly. The movements of the hand of the pianist, while passing from one key to another, are without influence on the sounds emitted.

On the other hand, in musical instruments of the radiophonic type, it is known to produce sounds without physical contact between the performer's hand and the sound producing parts. In this case, however, the performer must be very close to the apparatus (not more than several inches away), and in order simultaneously to modify two characteristics of sound, for example pitch and intensity, these radiophonic instruments, require, in principle, the intervention of two movable parts, i. e. the two hands of the performer. In addition, these instruments are not in commercial use, because they produce a progressive variation in sound pitch and thus include notes which are musically false. It is very difficult to avoid these false notes as a function of the position of the hand of the performer in space. It is still more difficult to attain the necessary precision in combination with dance movements.

The apparatus according to the invention has been conceived to permit the modification of two sound characteristics, pitch and intensity, for example, in a non-physical fashion, i. e. without contact with the sound apparatus and as a function of displacement in two different directions of the same movable member, for example, the hand of a performer carrying a signal light.

The sound modifications thus obtained occur in a continuous fashion as a result of the displacement of the signal light; the pitch of the sound varies stepwise i. e. passing by quarter tones, half tones or full tones, from one correct musical note to another, while avoiding intermediate false notes.

In the arrangement of the present invention use is made of a movable source of light, and means for modulating and transforming the light into musical sound waves. An objective lens system is employed to collect the light coming from the movable source into a narrow beam

2

and the beam is passed through one or another of a series of circularly disposed slits or perforations provided in a rotatable scanning disc. The spacing between the slits of one of the series 5 or tracks is different from the spacing in the other tracks, the spacing in each individual track being uniform and of predetermined magnitude depending on the rotational speed of the disc. Thus the slits in different tracks pass a given point at different frequencies and the light 10 passing through them excites musical notes of different pitch in the sound-transforming mechanism provided. This may conveniently comprise a photo-electric cell and an associated loud speaker system.

In accordance with the invention means are also provided for varying the intensity of the sound produced and comprise light screening means disposed along the optical axis of the 20 objective lens system in proximity to and of a width at least equal to the series of "sound tracks" on the scanning disc. The screening means provided has a substantially constant degree of opacity in the direction of a radius projected from the center of said disc parallel with the screening means, and a variable degree 25 of opacity in the transverse or tangential direction, so that when the source of light is moved in such transverse direction the produced musical note is varied in intensity by reason of the relatively greater or lesser amount of light which is transmitted through the screen to the scanning disc.

Thus when the source of light is moved in a 30 radial direction relative to the scanning disc, different musical notes are produced while movement in a tangential direction modifies the volume of the sound.

The "sound tracks" on the scanning disc being 35 so selected as to produce predetermined different frequencies, different musical notes of correct predetermined pitch will be separately produced as the light beam passes radially from one track to another. The intensity of the sound, on the other hand, will be continuous as the light beam 40 moves in a direction of radial transference from one "sound track" to another, so long as such radial movement is not accompanied by movement of the light beam in the direction tangential to the "sound track."

Thus the two variables are distinct and separate from each other and may be used in sequence to effect the widest variety of musical tones and intensities.

The light impulses passing through any

selected track in the scanning disc may be collected through a second appropriately disposed objective lens system for concentrating them onto the photo-electric cell. The harmonic content of the sound to be reproduced may be further controlled by the interposition of convergent lenses between the initial objective lens and the scanning disc as well as between the scanning disc and the second objective lens system referred to. Also masks as of the variable opacity type may be disposed between the second convergent lens system and the second objective lens system, to effect a still further modification of the harmonic content of the sound.

The drawings annexed hereto represent in a 15 schematical fashion and in the form of examples only, several embodiments of the invention.

Fig. 1 shows in perspective the arrangement of the various elements constituting an apparatus according to the invention.

Fig. 2 is a schematic drawing showing the position of the apparatus in relation to a performer.

Fig. 3 is a diagram showing the functional principle of the apparatus.

Fig. 4 is a partial view similar to that of Fig. 1 showing the arrangement of several accessory parts of the apparatus.

Fig. 5 represents a schematic plan view showing disposition of the principal parts of the apparatus shown assembled in Fig. 4.

Figs. 6 and 7 show two accessory devices permitting the performer to control his movements with respect to the sound producer.

Figs. 8, 9 and 10 show in perspective three particular devices for the production of light signals.

The apparatus represented schematically in Fig. 1 is actuated by one or more signal lamps 1 adapted to be carried by hand by one or more performers, for example by dancers. These 40 lamps may be provided with a reflector 2 or the like.

The apparatus itself comprises an objective lens or system of lenses 3 for receiving the light from source 1, the objective lens or system of lenses 3 concentrating the light into a narrow beam. When therefore the light source 1 is carried (Fig. 2) in the hand of a performer, moving in horizontal direction OX and in vertical direction OY, the image of the light source produced by the objective lens will describe a curve in a plane perpendicular to the optical axis of the objective lens. This curve such as curve C (Fig. 3) is inverted by the objective lens with respect to the curve described by the light source and each point of the curve corresponds to a predetermined sound pitch and a predetermined sound intensity, as will be described more fully below.

To the rear of objective lens 3, there are disposed a screen 4 and rotary disc 5 in close proximity to each other, said members being adapted to musically interpret the above mentioned two displacements of the light source.

Member 4 is a screen having a varied light transmitting power and it extends over the entire field to be scanned by the light beam from source 1. As shown in Fig. 1 the opacity of screen 4 is constant in a substantially horizontal direction i. e. parallel to a radius of the discs and varied in a vertical direction i. e. tangential to said radii, for example, increasing from the bottom to the top. It will be appreciated that in different dispositions of the screen 4 relative to the sound tracks 7 of the disc 5 the directions in which the

screen has constant and variable opacities will change. As shown in the drawings screen 4 is in the form of a prism.

Member 5 is a disc rotated at constant speed by an electrical motor 6, for example. On the periphery of disc 5, there are disposed several circular tracks over a width substantially equal to that of screen 4. These tracks are formed of perforations or slits 7. The number of slits 7 varies from one track to another. In each row or track the slits are equidistant from each other; three rows only are shown in Fig. 1 and six rows in Fig. 4. The slits in different rows pass a given point at different frequencies and therefore excite notes of different pitch.

Behind the disc 5, there may be arranged a light condenser 8 in the form of a lens or system of lenses which serves to concentrate the light rays passing members 4 and 5, upon a photo-electric cell 9. Cell 9 is disposed substantially in focus of condenser 8.

The light variations received by cell 9 are transformed into sound waves by a radio-electric amplifier 10 of well known construction, combined with a loud speaker 11. It is apparent that as a result of the disposition just described, the displacements of light source 1 in direction OX in the arrangement as shown in Fig. 1, will be translated into variations of intensity of the light beam passing screen 4 and disc 5, and consequently into variations of intensity of sound produced by photoelectric cell 9 and apparatus 10 and 11. The displacements in direction OX in the arrangement shown in Fig. 1, will produce a variation of light pulses per time unit reaching condenser 8 and photoelectric cell 9 since the light will move from one sound track to another. Thus there will result a variation in modulation or pitch of sound emitted by the radio-electric apparatus 10 and 11.

It is also apparent that all the positions of the movable lamp will be "tonalized" since the light impulses must pass through one or another specific sound track on the disc 5. At the same time, the variation in intensity will be regularly progressive as a function of the opacity of screen 4 while the variations in modulation will be discontinuous, because each of the sound tracks 7 comprises a number of slits determined as a function of the rotational speed of the disc. In this way, sounds are produced varying from one track to another by a half tone or a quarter tone, for example, i. e. by notes which are musically correct.

Fig. 2 shows the manner in which the optical axis Z-Z of objective lens or lens system 3 is preferably disposed, and along which members 4, 5, 8 and 9 are aligned.

This axis Z-Z is preferably slightly inclined above a horizontal plane in such a manner that the most frequent position of the hands carrying the signal lights, i. e. the position at the height of the breast, is approximately in the transversal optical symmetry plane of the objective.

It will be noted from Fig. 2 that the same apparatus such as described may be utilized to receive simultaneously several movable signals or light beams emitted by light sources carried by one or more dancers each causing a corresponding sound emission, with all these emissions being mixed in the radioelectric apparatus 10-11.

If it is desired to modify the harmonic content of sound emitted by the apparatus or to select arbitrarily a particular harmonic content,

the apparatus may be equipped with members such as represented in Figs. 4 and 5. These members consist of convergent lenses 12 disposed between objective lens 3 and screen 4 and extending over the entire width of the screen 4. It is possible to provide as many lenses 12 as there are perforated circular tracks 7 on disc 5. Each of these lenses have a rear surface formed in such a manner that the rays received thereon are made parallel to optical axis Z—Z.

Between disc 5 and condenser 8, there are also provided convergent lenses 13 corresponding to the number of perforated circular tracks 7 of disc 5. Lenses 13 redirect the luminous rays toward condenser 8. Finally between lenses 13 and disc 5, there are disposed as many masks 14 as there are perforated circular tracks 7. Each mask 14 is divided into an opaque zone and a transparent zone as shown in Fig. 4, such division occurs along a line the contour of which modifies the harmonic content of sound in accordance with principles well known in photographic sound recording. The masks 14 may also be of the varied opacity type.

Accordingly, the circular tracks of slits in disc 5 scan each mask 14, the height of which equals the distance between consecutive slits in each sound track. This procedure is well known.

Rotary disc 5 is preferably made of thin material which is relatively flexible so that during rotation the screen is maintained by the centrifugal force in a plane normal to the axis of rotation.

In the same manner as a pianist, for example, must take into account his position with respect to the piano, in the present case, the performer must be able to trace with respect to the instruments, his distance and lateral position—which is the purpose of system of Fig. 6—and also if necessary the position of the signals lights—which is the purpose of system of Fig. 7.

The apparatus assembly just described, i. e. members 3 to 11 and also 12, 13 and 14, is disposed in a box 15 (Fig. 6). On the front panel of box 15, there is placed the objective lens 3. Box 15 also comprises a sight member consisting for example of a white cross 16 placed over that front panel. In front of cross 16, an aim member is disposed in the form of an opaque cross 17 supported on arm 18 sliding in guide 19. With this a performer is able to verify his position with respect to the apparatus when cross 17 is projected or appears superimposed on white cross 16.

The adjustment of the aiming device is effected by adjusting the distance of aim member 17 with respect to the position of sight member 16. This is achieved by causing arm 18 to slide in guide 19. The aiming device may be provided with a luminous indicator such as represented in Fig. 7, and placed in the neighborhood of the apparatus. This luminous indicator is composed of several reflecting plates 20. Each plate corresponds to a musical note, i. e. to one of the perforated circular tracks 7 of disc 5, and is arranged with respect to the vertical plane passing through optical axis Z—Z of the musical instrument at such angle that each plate 20 reflects a luminous ray at the performer's eyes (represented as seen from above upon the drawing), i. e. appears luminous only if signal lamp 1 (Fig. 1) is in a position where its image as formed by objective 3, is projected upon the perforated circular track 7 corresponding to that particular plate.

It will be noted that the only connection existing between one of these plates 20 and one of the

perforated circular tracks 7 of the rotary disc 5 is the following:

As soon as light source 1 (Fig. 1) occupies a certain position in space, objective 3 produces an image thereof upon one of the perforated circular tracks 7. At the same time, the corresponding plate 20 (Fig. 7) reflects the rays of light source 1 into the eyes of the observer.

Fig. 8 shows a suitable form for a signal lamp. Lamp 1 has a filament which is as close to being a point source of light as possible, and is mounted with its reflector 2 in a blackened box 21 provided with a window 22. Window 22 is formed of glass which, if desired, may have a graded transparency, to vary the intensity of the beam of lamp 1 and thus the intensity of sound reproduced as a function of the angular or rotated orientation of the box 21 with respect to the plane Z—Z, that is, dependent upon the portion of the glass window 22 through which the light rays reaching the objective lens 3 have passed.

The particular signal lamp of Fig. 8 can be used in a musical play to effect a soft commencement of a note. It does not serve however, the same purpose as the variation of intensity of sound in accordance with the position of the lamp in space.

Box 21 is provided with a ring 23, preferably elastic, for fitting over the finger of the performer.

Lamp 1 may be supplied by electric cable 24 connected either to a fixed outlet or to a battery carried by the performer.

Fig. 9 shows an arrangement in which lamps 1 carried by the performer are supplied with energizing electric current from a radioelectric transmitter 25 the radiation from which is directed into the working plane of the performer and which is received by aerial 26 carried by the performer and connected to signal lamps 1 to excite them.

As shown in Fig. 10, signal lamp 1 may be replaced by a reflector of a standard type 27, to reflect the light of a fixed light source 28 to the objective 3. In this case, the image 29 formed by reflector 27 represents the movable light source 1 of Fig. 1.

What I claim is:

1. Apparatus for the light controlled production of musical sound waves comprising a movable light projector, means for modulating the light from said projector and means for transforming said modulated light into musical sound waves, said modulating means comprising an objective lens system for receiving and concentrating the light rays into a small beam having a direction which varies in accordance with the movement of the light projector, a rotatable disc mounted on an axis substantially parallel to the optical axis of said objective lens system, said disc having a series of circular bands of perforations of differing predetermined frequencies therein and positioned to move said perforations across the optical axis of said objective lens system in such a manner that when said light projector is moved in a direction which is parallel to a radial direction on said disc said beam passes from one circular band of perforations to another to change the pitch of the musical tone produced, and light screening means mounted near to said disc and across the optical axis of said objective, said screening means having a substantially constant degree of opacity in said radial direction and a varied degree of opacity in a transverse direction substantially at right angles to said radial

direction, whereby on movement of the light projector in said transverse direction the intensity of the musical tone produced is varied.

2. Apparatus according to claim 1 which includes an aiming device for a manipulator of said movable light source comprising a sight member disposed approximately perpendicularly to the optical axis of said apparatus and an adjustable aim member disposed in front of said sight member.

3. In a light-responsive musical sound producing system in which the selection of at least one of a series of musical notes is effected by projecting a light beam across the path of a selected track in a series of tracks of perforations provided in a moving surface, said perforations in each track having a predetermined uniform spaced relationship to cause light impulses to be transmitted through a given point on said moving surface at a given frequency, the spacing between the perforations being different for each track in accordance with the speed of movement of each track across the path of the beam to produce correctly pitched musical tones in said sound producing system; the improvement which comprises light screening means disposed in front of said tracks and having a constant light transmitting power in the direction of movement of the light beam from one track to another and a varied light transmitting power in a direction transverse to said first mentioned direction, whereby on movement of said beam along said transverse direction variations in said intensity are produced.

4. In a light-responsive musical sound producing system including a movable source of light, optical light-receiving means in the path of light from said source, an amplifying system, a photoelectric cell and a scanning disc having a series of circularly disposed radially spaced tracks of perforations for transmitting light impulses from said light-receiving means at selected frequencies to said cell; the improvement consisting of sound-intensity varying means comprising screening means formed of a light-transmitting medium disposed in the path of the light from said source to said disc, said medium having a substantially constant light-transmitting power in the radial direction of movement of said light from one track to another and having a varied light-transmitting power in a direction tangential to said first mentioned direction, whereby on movement of said light along said tangential direction variations in sound intensity are produced.

5. In a light-responsive musical sound producing system as set forth in claim 3 and further including at least one movable light source for projecting the light beam and an objective lens system positioned between the light source and the moving surface for receiving light rays from the source and for concentrating such rays into a relatively thin beam having a direction which varies according to the position of the source; the light screening means as set forth in claim 3 in combination with a series of convergent lenses disposed between the objective lens system and said screening means equal in number to the number of tracks on the moving surface, said convergent lenses having inclined rear surfaces for directing light rays passing therethrough from the objective lens system along paths parallel with the optical axis of the objective lens system and toward said screening means.

6. In a light-responsive musical sound produc-

ing system; the combination as set forth in claim 5 and further comprising a series of masks equal in number to the number of tracks of perforations and disposed across the paths of the light rays and in alignment with the respective tracks, each mask being of varied opacity.

7. In a light-responsive musical sound producing system; the combination as set forth in claim 5 further comprising a series of masks equal in number to the number of perforations, each mask having a relatively opaque zone and a relatively transparent zone divided on a line for modifying the harmonic content of the sound to a predetermined degree, said masks being disposed across the path of the light rays with each mask in alignment with its respective track of perforations.

8. In a light-responsive musical sound producing system; sound intensity varying means as set forth in claim 4 in combination with aiming means for a manipulator of the movable light source, said aiming means comprising a sight member disposed substantially perpendicularly to the optical axis of the light-receiving means, and an adjustable target member disposed in front of said sight member.

9. In a light-responsive musical sound producing system; the combination as set forth in claim 7 further comprising a series of reflecting plates of a number equal to the number of tracks on said moving surface, said reflecting plates being disposed with respect to a manipulator of said movable light source to reflect light rays back to said manipulator in consonance with the beaming of the rays for transmission through any selected one of the tracks of perforations.

10. In a light-responsive musical sound producing system; light screening means according to claim 3 in combination with a screen having regions of different transparency extending over the source of light.

11. Apparatus for the light controlled production of musical sound waves as set forth in claim 1; wherein said rotatable disc is formed of a relatively thin and flexible material.

12. Apparatus for the light controlled production of musical sound waves as set forth in claim 1; wherein said light projector includes a fixed light source and a movable reflector for receiving light from said source and reflecting said light to said objective lens system.

13. Apparatus for the light controlled production of musical sound waves as set forth in claim 1; wherein said light projector includes a radioelectric wave transmitter, a portable antenna disposed in the field of said transmitter, and an electric lamp operatively connected to said antenna to be energized in response to the transmitted radio-electric wave.
